UNITED STATES PATENT OFFICE

152,483

DESIGN FOR A GAS HEATER

Jay Fred King, Marietta, and Joseph Newman White, Atlanta, Ga., assignors to The Atlanta Stove Works, Inc., Atlanta, Ga.

Application January 26, 1948, Serial No. 144,043

Term of patent 14 years

(Cl. D81—10)

To all whom it may concern:

Be it known that we, Jay Fred King, a citizen of the United States of America and resident of Marietta, in the county of Cobb and State of Georgia, and Joseph Newman White, a citizen of the United States of America and resident of Atlanta, in the county of Fulton and State of Georgia, have invented a new, original, and ornamental Design for a Gas Heater, of which the following is a specification, reference being had to the accompanying drawings, forming a part thereof.

In the drawings:

Figure 1 is a front perspective view of a gas heater, showing our new design,

Figure 2 is a side perspective view, looking toward the right hand side in Figure 1,

Figure 3 is a rear elevation of the heater, and

Figure 4 is a side perspective view, looking toward the opposite or left hand side in Figure 1.

Figure 5 is a transverse section taken on the line 5—5 of Figure 1.

We claim:

The ornamental design for a gas heater, substantially as shown.

JAY FRED KING.

JOSEPH NEWMAN WHITE.
